CLAIM

The ornamental design for a packaging, as shown and described.

DESCRIPTION

FIG. 1 is a top perspective view of a first embodiment of packaging, showing my new design;

FIG. 2 is a top plan view of the packaging shown in FIG. 1;

FIG. 3 is a front view of the packaging shown in FIG. 2;

FIG. 4 is a rear view of the packaging shown in FIG. 2;

FIG. 5 is a right side view of the packaging shown in FIG. 2;

FIG. 6 is a left side view of the packaging shown in FIG. 2;

FIG. 7 is a top perspective view of a second embodiment of packaging, showing my new design;

FIG. 8 is a top perspective view of a third embodiment of packaging, showing my new design;

FIG. 9 is a top perspective view of a fourth embodiment of packaging, showing my new design;

FIG. 10 is a top perspective view of a fifth embodiment of packaging, showing my new design;

FIG. 11 is a front view of the packaging shown in FIG. 10;

FIG. 12 is a right side view of the packaging shown in FIG. 11;

FIG. 13 is a left side view of the packaging shown in FIG. 11;

FIG. 14 is a top plan view of the packaging shown in FIG. 11;

FIG. 15 is a bottom view of the packaging shown in FIG. 11; and,

FIG. 16 is a top perspective view of a sixth embodiment of packaging, showing my new design.

The evenly broken lines represent both parts of the article as well as environmental subject matter of exemplary packaging. The dot-dash line represents the boundaries of the claim. None of the broken lines form part of the claimed design.

1 Claim, 13 Drawing Sheets
